UNITED STATES PATENT OFFICE.

ARTHUR EDWARD PAGET AND CHARLES EDWARD PAGET, OF HUNTSVILLE, ONTARIO, CANADA.

GRAIN-CAR DOOR.

Application filed December 26, 1922. Serial No. 609,083.

To all whom it may concern:

Be it known that we, ARTHUR EDWARD PAGET and CHARLES EDWARD PAGET, both subjects of the King of Great Britain, and both residents of the town of Huntsville, in the district of Muskoka, in the Province of Ontario, Canada, have invented certain new and useful Improvements in Grain-Car Doors, of which the following is the specification.

Our invention relates to improvements in grain car doors and the object of the invention is to devise means for preventing distortion or bulging of the door under the influence of the weight of the grain in the car.

A further object is to devise bracing means which will prevent the door bulging out of its plane shape.

Our invention consists of a grain car door constructed and arranged all as hereinafter more particularly described and illustrated in the accompanying drawing in which:

Fig. 1 represents an elevational view of the outside of the door, showing our bracing means applied thereto.

Fig. 2 is a horizontal section through the line 2—2 Figure 1.

Fig. 3 is an elevational view of a door showing a modified form of bracing device applied thereto, and

Fig. 4 is a horizontal section through the line 4—4 Figure 3.

Like characters of reference indicate corresponding parts in the different views.

1 is the frame of the door and 2 are the boards forming the body portion of the door and preferably secured to the inside of the frame 1. 3 is a vertical strut extending between the horizontal members of the frame 1 and suitably secured thereto by bolts 4 extending through the plates 5 which are in turn secured to the ends of the struts.

6 is a bow shaped brace straddling the strut 3 and having its ends abutting the vertical members of the frame 1. 7 is a bowed strap corresponding in shape to the shape of the bowed brace 6, but having its ends extending over onto the outside faces of the vertical members of the frame 1 of the door and being secured thereto by means of the bolts 8. 9 are bolts extending through the strap 7 which is preferably constructed of metal and through the brace 6 and the door boards 2 as is clearly shown

in Figure 2. The brace 6 is preferably constructed of wood.

In the modified form illustrated in Figure 4, two struts 3 are provided and the intermediate portion of the wooden brace 6 straddles both, its ends abutting the vertical members of the frame 1, being held in place as above described.

In grain car doors previously constructed of this type it has been found that there was a tendency for them to bulge in the vicinity of their centre, due to the weight of the grain in the car and consequently by applying the struts 3 in the manner above described and using the wooden braces 6 and straps 7 to straddle them, any such distortion is prevented, thus keeping the door in its plane shape.

Although we have described our bracing means as constituting a single wooden bracing member and an iron strap we could with equal facility use two or three bowed members, depending on the strength required. Also as illustrated, we could use two or more struts and have one bracing member or more, straddling the same.

In addition instead of the bowed braces 6 and straps 7 extending horizontally as illustrated, they could extend vertically and the struts 3 be disposed horizontally.

From the above description it will be seen that we have devised a simple and effective bracing means for grain car doors which will effectively prevent the distortion thereof so prevalent in the type illustrated.

What we claim as our invention is.

1. In a grain car door, the combination with vertical and horizontal members of the door frame, of a strut disposed between such horizontal members and secured to each, a bowed brace straddling the strut and having its ends engaging the opposed side edges of the vertical door frame members, a second bowed brace applied to the first bowed brace and having its ends overlying the vertical members of the door frame, means for securing the second mentioned brace to the first mentioned brace and means for securing the second mentioned brace to the vertical members of the door frame.

2. In a grain car door, the combination with vertical and horizontal members of the door frame, of a strut disposed between

such horizontal members and secured to each, a bowed brace straddling the strut and having its ends engaging the opposed side edges of the vertical door frame members, a second bowed brace applied to the first bowed brace and having its ends overlying the vertical members of the door

frame, bolts securing the second mentioned brace to the first mentioned brace and bolts securing the second mentioned brace to the 10 vertical members of the door frame.

ARTHUR EDWARD PAGET.
CHARLES EDWARD PAGET.
